UNITED STATES PATENT OFFICE

JOHN E. BURKE, OF FOND DU LAC, WISCONSIN

RADIATOR COVER AND HUMIDIFIER

Application filed December 19, 1927. Serial No. 241,066.

My invention belongs to that general class of devices known as radiator cabinets, casings or enclosures and relates more particularly to a cabinet of the kind described which 5 may be made up in a desired length and height and at installation be readily adjustable to fit the radiator and allow for any slight warping or irregularity in the radiator. The invention has among its objects 10 the production of a device of the kind described that is simple, inexpensive, attractive, efficient, durable, adjustable, of light weight and satisfactory wherever found applicable.

It has among its further objects the production of an improved device of the kind 15 described provided with a humidifying pan and with a top or cover that may be lifted to permit inspection or refilling of the humidifying pan. In its preferred form, it is 20 constructed so that it may be partially knocked down for convenience in storage or shipping.

Many other objects and advantages of the 25 construction herein shown and described will be obvious to those skilled in the art from the disclosure herein given.

To this end my invention consists in the novel construction, arrangement and combination of parts herein shown and described, 30 and more particularly pointed out in the claims.

In the drawings, wherein like reference 35 characters indicate like or corresponding parts:

Fig. 1 is a front elevation of my improved device showing its application;

Fig. 2 is a sectional view taken substantially on line 2—2 of Fig. 1;

Fig. 3 is a sectional view taken substantially on line 3—3 of Fig. 1;

Fig. 4 is a sectional view taken substantially on line 4—4 of Fig. 1; and

Fig. 5 is a sectional view taken substantially on line 5—5 of Fig. 2.

Referring to the drawings in which only one embodiment of the invention is shown, the cabinet or enclosure consists of a top or cover 1, a back or rear portion 2, a front portion 3 and end members 4 and 5. The 45 end members are preferably each in the form

of an angle, the portion 4 being adapted to rest upon the top of the radiator and form a support for the humidifying pan and the portion 5 for connection with the front and rear portions as will be described hereinafter. The rear portion 2 shown is flanged at the ends as indicated at 7, the outer edges of the flanges being turned inwardly as shown at 8 to provide a finish. Secured to the top portion 2 and the flanges 7 are angular corner pieces 9—10. In the drawings, I have illustrated the portion 10 adjustably connected to the part 5, either one or both corner pieces or the corner 10 and the part 5 being slotted as indicated at 11 and 12, respectively, 55 bolts 14 securing the parts together. I have also shown brackets 15—16 secured to the back. These brackets are so arranged that the parts 4 may rest thereon. When it is not desired that the back be adjustably secured to the end members 5, the adjustable connection between the corner portions 10 and the parts 5 may be omitted and the parts 60 be spot welded or otherwise secured by corner parts 10 to the brackets 16. As shown, 65 the top edge of the back plate 2 is preferably flanged over as indicated at 17 with the free edge folded inwardly thereby stiffening the structure. The parts 5 are preferably cut 70 away as indicated at 18 so as not to interfere with the turned over portion 17.

While the front section or portion 3 be 75 of any desired length it is preferably made somewhat smaller than the rear section 2. The lower edge 19 is preferably turned inwardly to stiffen the same and provide a finish and the top edge preferably flanged over as indicated at 20 with the free edge of the flange folded inwardly as shown at 85 21. Corner members 23—24 similar to those 90 at the rear are provided at the front and these may be connected to the end members 5 by slot and bolt connections similar to those described for the back. I prefer to provide the front section with an opening 25 adjacent the top edge and a somewhat larger opening 26 below, the opening 26 being covered by a perforated plate or sheet 28, this being ordinarily perforated or formed to imitate or represent cane. The plate 28 is shown 95 100

with its top and bottom edges folded over so as to engage the turned over portions 27 at the bottom and top of opening 26. The front side 24 of the corner piece is preferably turned in at the opening to also provide a finish.

The cover 1 is formed with a flanged edge 29 at the back and flanged edges 30 at the front and ends, the cover being proportioned 10 so that it preferably projects slightly beyond the front face of the front 3 as most clearly shown in Figs. 2 and 4. The cover is hinged to the back 9 by the hinges 31. The hinge parts may be secured to the cover and to 15 the back by rivets 32 and bolts 33 or in an equivalent manner. When secured to one part by bolts, the same may be removed when packing or shipping and yet be readily assembled at the time of installation.

20 As shown, there is provided a pan 34 for containing water, or the like, the same constituting a humidifier. This pan is of a size to extend from end to end of the device but is preferably somewhat narrower than the 25 cabinet. The same is supported by the flange portions 4 and may be adjusted forward or back, the same ordinarily being positioned at the back or in an intermediate position. The cabinet may be given any suitable finish, 30 frequently the same being so finished as to resemble oak, mahogany, walnut or in other words, so as to harmonize with the wood-work or furnishings of the room.

I have found that there often may be a 35 slight variation in the width of the radiator coils for some reason or other, or the radiator unit has warped or bowed so that the sections are out of alignment to an appreciable extent. It is desired that the cabinet mounted on the same fit tightly and in a way grip or clamp the radiator rather than merely set thereon. With my improved construction, the cabinet may be mounted upon the radiator and may then be adjusted so that it 40 grips or closely fits the same and even adjusted so that it is practically clamped on the radiator. Where no adjustment is provided and the radiator cabinet fits tightly if the same is forced into place, it frequently 45 distorts the cabinet and causes a bend or buckling at the front. Obviously, in a nicely finished cabinet, a buckling would immediately ruin the same so far as its ornamental appearance was concerned. By making my cabinet adjustable, this difficulty is 50 entirely avoided and at the same time, I am enabled to fit the same very closely or clamp it to the radiator so that it is not easily displaced. The device shown is particularly ornamental and provides a very 55 efficiently concealed humidifier. The use of radiator cabinets is well known consequently I do not feel it necessary to point out all the uses of such a cabinet, the three outstanding features being improved appearance

of the radiator, the deflecting of the heated air currents outwardly and the resulting preservation of the walls and ceilings of the room.

Having thus described my invention, it is 70 obvious that various immaterial modifications may be made in the same without departing from the spirit of my invention; hence I do not wish to be understood as limiting myself to the exact form, construction, arrangement 75 and combination of parts herein shown and described, or uses mentioned.

What I claim as new and desire to secure by Letters Patent is:

1. In a radiator cover, the combination of a 80 frame comprising front, rear and side portions, said side portions comprising angle members for supporting a pan thereon, corner pieces secured to said front and rear portions and adapted to be adjustably secured to 85 said angle members, and a cover disposed over said frame.

2. In a radiator cover, the combination of a 90 frame comprising front, rear and side portions, said side portions comprising angle members for supporting a pan thereon and having slots formed therein, corner pieces secured to said front and rear portions and having means associated therewith adapted to engage said slots for adjustably securing said 95 corner pieces to said angle members, and a cover disposed over said frame.

3. In a radiator cover, the combination of a 100 frame comprising front, rear and side portions, said side portions comprising angle members for supporting a pan thereon, corner pieces secured to said front and rear portions and having slots formed therein, said members having means associated therewith adapted to engage said slots for adjustably 105 securing said angle members to said corner pieces, and a cover disposed over said frame.

4. In a radiator cover, the combination of a 110 frame comprising front, rear and side portions, said side portions comprising angle members for supporting a pan thereon and having slots formed therein, corner pieces secured to said front and rear portions and having slots formed therein adapted to register with the slots formed in said angle members, means engaging said slots for securing said corner pieces and angle members together, and a cover disposed over said frame.

5. In a radiator cover, the combination of a 115 frame comprising front, rear and side portions, said side portions comprising angle members for supporting a pan thereon and having slots formed therein adjacent their end portions, corner pieces secured to said front and rear portions and having slots formed therein adapted to register with the slots formed in said angle members, means engaging said slots for adjustably securing said corner pieces and angle members together, and a cover hinged to said rear por- 120

130

tion and disposed over said frame in a manner to conceal said corner pieces, angle members and securing means.

6. In a radiator cover, the combination of a frame having a front portion and a rear portion adjustable toward and from each other, angular corner pieces having slots formed therein and secured to said front and rear portions adjacent the ends thereof, angle members having slots formed therein adjacent the ends thereof adapted to register with the slots formed in said corner pieces, securing means engaging said slots and operatively related to said corner pieces and angle members in a manner to secure said front and rear portions in adjusted position with respect to each other, and a cover disposed over said portions and angle members.

In testimony whereof, I have hereunto signed my name.

JOHN E. BURKE.
